BOTTOM LOCK FOR CARTONS

Joseph Vesak, Richmond, British Columbia, Canada, assignor to Crown Zellerbach Canada Limited, Vancouver, British Columbia, Canada, a corporation of Canada

Filed June 5, 1961, Ser. No. 114,831

Claims priority, application Canada June 6, 1960

4 Claims. (Cl. 229—45)

This invention relates to locks for temporarily holding the flaps of the bottoms of cartons in the closed position.

Although this invention may be used with any type of carton having bottom flaps, it is particularly for cartons having top and bottom flaps that are glued or otherwise secured in closed positions after the carton has been loaded with bottles or the like. This loading usually takes place in specially designed machines. These cartons are delivered to the users in collapsed or flattened condition. During the loading operation prior to this invention, each carton was opened up and the bottom flaps folded into their normal closed positions. The carton was placed on its bottom on a conveyor for delivery to the loading machine. After the carton was loaded, it was moved out of the loading machine, and the bottom flaps were opened up by a standard plow, a well-known type of equipment in this industry. After glue was applied to the top and bottom flaps, these flaps were folded inwardly and pressed into their final closed positions.

The difficulty in the past has been that after the bottom flaps had been moved into closed position the first time and the carton placed on the conveyor, the bottom flaps had a tendency to spring out of position, resulting in many cartons falling over or being tipped out of the correct position for loading.

The main purpose of the present invention is to overcome the above difficulty in a simple and efficient manner. This is accomplished in such a simple way that the person who folds the bottom flaps inwardly automatically locks these flaps in position with very little more than normal effort and without any loss of time.

The cartons to which this invention is applied have inner and outer bottom flaps connected to the carton side walls and foldable inwardly into partial overlapping relationship. A bottom lock according to the present invention for this type of carton comprises a slot in the inner flap adjacent the inner edge thereof. This slot forms flap sections that are displaceable relative to each other out of the general plane of the flap. When the outer bottom flap is folded over the inner flap, the two flaps are simultaneously pressed inwardly of the carton beyond the normal positions assumed by said flaps when closing the carton bottom. The slot in the inner flap is so arranged that this inward movement of the flap either results in relative displacement of the flap sections or enables the operator to displace one flap section relative to another, and when the flaps are released, the inner edge of the outer bottom flap moves between the displaced flap sections to lock the inner and outer flaps together. In other words, in order to lock the flaps together, the action substantially is to press them

2

inwardly of the carton a little beyond their normal positions, and then to release them. During this action, the flap sections are displaced relative to each other so that the inner edge of the outer flap may move between these sections where it is trapped.

Examples of this invention are illustrated in the accompanying drawings, in which,

FIGURE 1 is a perspective view of the bottom portion of a carton with the flaps thereof in the open position, 10 and illustrating a preferred form of the invention,

FIGURE 2 is a bottom plan view of the carton with the inner flap folded into its normal closing position,

FIGURE 3 is a bottom plan view with the outer bottom flap folded into its normal closing position,

FIGURE 4 is a similar view showing the bottom flaps pressed inwardly of the carton just before they are released,

FIGURE 5 is a similar view showing the bottom flaps after they have been released and locked in the closed position,

FIGURE 6 is an enlarged section taken on the line 6—6 of FIGURE 4,

FIGURE 7 is an enlarged section taken on the line 7—7 of FIGURE 5,

FIGURE 8 diagrammatically illustrates a carton with its bottom flaps locked closed approaching a plow,

FIGURE 9 is a view similar to FIGURE 1, illustrating an alternative form of the invention,

FIGURE 10 is a bottom plan view of the carton of FIGURE 9 with the flaps in the closed and locked position,

FIGURE 11 is a view similar to FIGURE 9, illustrating a variation of the carton of the latter figure, and

FIGURE 12 is a bottom plan view of the carton of FIGURE 11 with the bottom flaps closed.

Referring to FIGURES 1 to 7 of the drawings, 10 is a standard carton having side walls 11 and 12, and end walls 13 and 14. End flaps 17 and 18 are usually integrally connected with end walls 13 and 14, respectively, and are foldable inwardly thereof. Inner and outer bottom flaps 22 and 23 are integrally connected to side walls 11 and 12 and are foldable inwardly therefrom. When carton 10 is closed, end flaps 17 and 18 are first folded inwardly, then flap 22 is folded over the end flaps, after which flap 23 is folded over and partially overlaps flap 22. These flaps are glued or otherwise secured together in the well-known manner.

The bottom lock of FIGURES 1 to 7 comprises a slot 30 in inner flap 22 adjacent the inner edge 31 thereof and preferably about midway between the ends of the flap. The illustrated slot 30 is substantially Y-shaped so that it has a substantially V-shaped upper part 33, and a straight lower part 34 extending away from the apex of the V. It is preferable that the bottom part 34 of the Y extends to and opens out through the inner edge 31 of the inner flap. This provides the best results, although the entire Y-shaped slot may be shifted inwardly a little from the flap edge 31. In addition to this, the lock can be worked if only the V-shaped upper part 33 of the slot is used. The apex of the slot always extends towards the inner edge 31 of the flap, and it may even extend to said inner edge.

The V-shaped upper part 33 or slot 30 forms a sub-

stantially V-shaped flap section 37, while the bottom part 34 of the slot forms on the opposite sides thereof flap sections 38 and 39 which are displaceable relative to each other and to the V-shaped flap section 37.

When it is desired to place carton 10 on the bottom thereof on a conveyor or other support prior to the loading of the carton, end flaps 17 and 18 are folded inwardly, and inner bottom flap 22 folded over them, as shown in FIGURE 2. Then outer bottom flap 23 is folded inwardly over flap 22 in the usual manner, at which time it partially overlaps the latter flap, as shown in FIGURE 3. In order to lock the bottom flaps closed, it is only necessary to press said flaps near the centres of the inner edges thereof inwardly beyond the general plane of said flaps, said plane being indicated by line 15 42 in FIGURE 6. It will be noted that at this time the inner edge of outer bottom flap 23 presses against the portion of inner flap 22 extending along the inner edge 31 thereof. This takes place midway between the ends of the flaps. As the ends of the flaps are bearing against end flaps 17 and 18, said ends tend to stay in the normal plane of the bottom flaps. As a result of this, when pressure is applied to the outer flap near the centre thereof, flap sections 38 and 39 which are weakened by the lower part 34 of slot 39, move inwardly 20 relative to flap section 37, as clearly illustrated in FIGURE 6. When the pressure against the flaps is released, they tend to swing back to their positions generally in the plane indicated by line 42. At this time, the inner edge 44 of outer flap 23 tends to swing through the arc indicated by line 45 in FIGURE 6. This causes edge 44 to move beneath flap section 37 where it remains when the flaps return to their normal closed position, as shown in FIGURE 5. Thus, the inner edge 35 44 of the outer flap is trapped between flap section 37 and flap sections 38 and 39 of the inner flap. This retains the bottom flaps in a general horizontal plane so that carton 10 will sit properly on the bottom flaps, without tilting or falling over.

After carton 10 is filled in the usual manner, it is shifted towards a plow 48 which moves into opening 46 between end flap 17 or 18 and the bottom flaps 22 and 23. The plow is shaped to swing the bottom flaps outwardly relative to the side walls of the carton so that glue may be applied thereto. At the same time, glue is applied to the top flaps of the carton in accordance with standard practice, after which the top and bottom flaps are folded inwardly to close and seal the top and bottom of the carton. This operation is standard practice and does not require any special description herein.

FIGURES 9 and 10 illustrate an alternative form of bottom lock incorporated in a carton 55 having bottom end flaps 56 and 57, and inner side bottom flap 58, and an outer side bottom flap 59. The lock in this form of the invention comprises a slot 62 in outer flap 58 preferably about midway between the ends thereof and extending to and opening out through the inner edge 65 of the flap. This slot forms flap sections 67 and 68 on opposite sides thereof which are relatively displaceable.

In order to lock the bottom flaps of carton 55 in the closed position, end flaps 56 and 57 are first folded inwardly, after which inner and outer bottom flaps 58 and 59 are consecutively folded inwardly into partial overlapping relationship. Then outer flap 59 is pressed inwardly near the inner edge 60 thereof to move both bottom flaps inwardly of the carton beyond their normal positions. The inward movement of the outer flap is continued until the edge 60 of the outer flap moves inwardly past the edge 65 of the inner flap. At this time, the operator depresses either of the flap sections 67 or 68, for example, section 67, and then the pressure on the flaps is released. As the outer flap swings back to its normal position, it swings beneath flap section 70 75

68 and over flap section 67 so that the outer flap is trapped between said flap sections. This results in the inner and outer bottom flaps being locked together substantially in the general plane of the flaps when they are in their normal closed position. From here on, the carton is treated in the same manner as carton 10 described above.

If the bottom part 34 of slot 30 of carton 10 is omitted, the locking operation is the same as above, excepting that the operator may have manually to displace flap section 37 outwardly of inner flap 22 in order to be sure that the edge 44 of outer flap 23 moves beneath said flap section when the pressure on the bottom flaps is released.

FIGURES 11 and 12 illustrate a variation of the bottom lock of FIGURES 9 and 10. Side bottom flaps 58a and 59a of carton 55a are a little wider than flaps 58 and 59 of carton 55. Flap 58a has slot 62a therein, while flap 59a has a corresponding slot 72 about midway between the ends thereof and opening out through its inner edge 73. The latter slot forms flap sections 75 and 76 on opposite sides thereof.

When flaps 58a and 59a are swung inwardly, the operator depresses a flap section of each relative to other flap section of its flap. For example, flap sections 67a and 75a are depressed, and the inner edges of the flaps are manipulated so that flap sections 68a and 76 overlie sections 75 and 67a, respectively, as shown in FIGURE 12. This locks bottom flaps 58a and 59a together.

From the above it will be seen that the present bottom lock is extremely simple, and yet it efficiently holds the inner and outer bottom flaps of the cartons in their normal closed positions. The operator has very little more to do than to fold the inner and outer flaps consecutively into their closed position. He merely presses the flaps inwardly of the carton beyond their normal positions. With this form of the invention illustrated in FIGURES 1 to 7, the actual locking takes place automatically when the operator releases the inwardly-pressed bottom flaps. With the alternative of FIGURES 9 and 10, he merely has to depress one of the flap sections 67 or 68 after he has pressed the bottom flap inwardly. Once this is done, the locking takes place automatically upon release of the bottom flaps. In both cases, the natural tendency of the bottom flaps to swing back and outwardly relative to the carton, causes the flaps to lock together. This lock, however, is such that it is very easy to force the bottom flaps outwardly relative to the carton in order to release the lock.

What I claim as my invention is:

1. An end closure lock for cartons having side walls, comprising inner and outer flaps connected to opposite carton walls, said flaps being of a size to overlap a little at inner edges thereof when folded inwardly relative to the carton, a substantially Y-shaped slot in the inner flap with the part of the slot forming the bottom of the Y extending to and opening out through the inner edge of the inner flap, the upper part of the Y slot forming a substantially V-shaped first flap section and the bottom part of the Y forming on opposite sides thereof second and third flap sections that are displaceable relative to each other and to the first flap section, whereby when the outer flap is pressed inwardly over the inner flap beyond the normal positions of said flaps, the second and third flap sections move relative to each other and are depressed relative to the first flap section, and when the outer flap is released the inner edge thereof moves over the second and third flap sections and beneath the first flap section releasably to lock the inner and outer flaps together.

2. An end closure lock for cartons having side walls, comprising inner and outer flaps connected to opposite side walls, each of said flaps being free from tabular projections on their inner edges, said flaps foldable inwardly and being of a size to overlap at their inner edges

such that when folded inwardly one flap is an inner flap and the other is an outer flap, a slot in the inner flap forming a first flap section having an edge freed from the remainder of the inner flap, said first flap section extending towards the inner edge of said inner flap, and a slit in the inner flap extending from the inner edge thereof to a point intermediate the ends of the slot in said inner flap, said slit forming second and third flap sections being movable downwardly relative to the first flap section and away from each other, whereby when 10 the outer flap is pressed inwardly over the inner flap beyond the normal positions of said flaps, the second and third flap sections move away from each other and are depressed relative to the first flap section, and when the outer flap is released the inner edge thereof moves 15

over the second and third flap sections and beneath the first flap section releasably to lock the inner and outer flaps together.

3. A lock as claimed in claim 2 wherein said slot forming the first flap section is V-shaped.

4. A lock as claimed in claim 3 wherein the slit extends to the apex of the V-shaped slot.
